UNITED STATES PATENT OFFICE.

JOHN S. WORTH, OF COATESVILLE, PENNSYLVANIA, ASSIGNOR TO HIMSELF AND
WILLIAM P. WORTH, OF COATESVILLE, PENNSYLVANIA.

ROLLING-MILL.

1,206,746.

Specification of Letters Patent.

Patented Nov. 28, 1916.

Original application filed September 28, 1915, Serial No. 53,095. Divided and this application filed July 6, 1916. Serial No. 107,810.

To all whom it may concern:

Be it known that I, JOHN S. WORTH, a citizen of the United States, and a resident of Coatesville, county of Chester, State of Pennsylvania, have invented certain Improvements in Rolling-Mills, of which the following is a specification.

My invention relates to certain improvements in means for driving the rolls of a rolling mill.

The main object of my invention is to provide means for independently driving the working rolls of the mill and to eliminate the gearing.

15 A further object of the invention is to dispense with the frequent dressing and sizing of the rolls and to improve the product by obliterating the infinitesimal waves which are formed in the plates due to the 20 lost motion in the gearing.

This application is a division of an application filed by me on the 28th day of September, 1915, under Serial No. 53,095.

In the accompanying drawings:—Figure 25 1, is a side view of a three-high mill in which supporting rolls are used and illustrating my improved means for independently driving the working rolls; Fig. 2, is a sectional view on the line 2—2, Fig. 1; Fig. 30 3, is a side view, showing the housings in dotted lines, of a three-high mill and illustrating the independent driving means; Fig. 4, is a sectional view on the line 4—4, Fig. 3; Fig. 5, is a side view of a two-high mill and showing the housings in dotted lines and illustrating the independent drive; and Fig. 6, is a sectional view on the line 35 6—6, Fig. 5.

In the above noted application I have 40 claimed broadly the idea of the independent drive, whether the working rolls are driven indirectly through the supporting rolls or whether driven directly. In the present application, I have limited the claims to the 45 independent direct driving of the rolls.

Referring in the first instance to Figs. 1 and 2, 1 is the lower working roll and 2 is the upper working roll. 3 is the intermediate roll. 4 is the lower supporting roll 50 and 5 is the upper supporting roll. These rolls are mounted in housings and the pressure is regulated by set screws 7 at the upper ends of the housings. In the present instance, I have illustrated a horizontal steam

engine as a driving element, but it will be 55 understood that electric motors, or other types of engines, may be used without departing from the essential features of the invention. 8 is the engine having a crank shaft 11, which is connected to the upper 60 working roll 2 by a coupling shaft 12. The couplings 12^a are of the ordinary flexible type. 9 is an engine having a crank shaft 14 which is connected to the lower working roll 1 by a coupling shaft 15. The couplings 15^a of this shaft are of the ordinary construction. In this case, the intermediate roll 3 is not driven. By this construction, 65 it will be seen that the engine or motor 8 directly drives the roll 2 without the use 70 of intervening gearing and the engine 9 drives the working roll 1 without the use of intervening gearing. These engines can be so designed and set that the surface speed of both rolls will be the same. Thus 75 the ordinary gearing that is now universally used in rolling mill practice for rolling plates and other products is entirely dispensed with. When the rolls are driven through the gearing they must have the 80 same proportion one to another that the gears bear to each other. When one roll is dressed then the other roll must be dressed so as to keep the diameters the same, as otherwise it will cause a breakage of the 85 gears and if the rolls vary in surface speed, as would be the case where one roll is slightly greater in diameter than the other, the surface of the plate would have the infinitesimal waves, which are objectionable, and 90 which cannot be avoided in the present method of driving the rolls.

I have found that, by independently driving the rolls and so regulating the driving means that the surface speed of the rolls is 95 the same, I obliterate entirely the infinitesimal waves and produce an exceedingly satisfactory product.

In Fig. 1, I have illustrated a three-high rolling mill using supporting rolls for the 100 working rolls. These rolls are used to support the driving rolls, consequently, the driving rolls can be much less in diameter than rolls which are not supported and where they of considerable length.

105 In the pending application, of which this is a division, I have illustrated a method of driving in which the working rolls are

driven through the supporting rolls and in which the intermediate roll is also driven in some instances.

In Figs. 3 and 4, I have illustrated a three-high mill in which the working rolls 1^a and 2^a are driven by independent engines 9^a and 8^a, respectively. The intermediate roll is driven through either one of the working rolls.

In Figs. 5 and 6, I have illustrated a two-high roll in which the rolls 1^b and 2^b are independently driven by separate engines 9^b and 8^b. As stated above, instead of the steam engines, as indicated in diagram in the drawings, electric motors may be used without departing from the spirit of the invention.

It will be seen that by driving the rolls independently and at the same speed the diameter of the rolls need not be the same and one roll can be of a greater diameter than the other, so long as the engine is regulated so that the surface speed of the rolls is the same. Therefore, the rolls can be used until the chill is entirely worn away. In practice, one roll wears away more rapidly than another and when one roll is slightly worn the other roll must be dressed

to the same diameter as the worn roll, but where an independent drive is used this is not necessary and each roll can be used without dressing until completely worn.

While I have illustrated the two engines 8 and 9 as being of the ordinary type of reciprocating engines, it will be understood that they may be arranged as compound engines, one cylinder driving one roll and the other cylinder driving the other roll.

I claim:

1. The combination in a rolling mill, of two working rolls; and means for independently driving each of said rolls so that the surface speed of each working roll will be the same.

2. The combination in a rolling mill, of two working rolls and an intermediate roll; and independent means for driving each of said working rolls.

3. The combination in a rolling mill, of two working rolls; a supporting roll for each working roll; and means for independently driving each working roll so that the surface speed of the working rolls will be the same.

JOHN S. WORTH
